UNITED STATES PATENT OFFICE.

FRANK T. DICKINSON, OF TOLEDO, OHIO.

BRAKE-SHOE.

1,308,402.

Specification of Letters Patent.

Patented July 1, 1919.

Application filed February 15, 1909, Serial No. 477,859. Renewed February 10, 1917. Serial No. 147,930.

To all whom it may concern:

Be it known that I, FRANK T. DICKINSON, a citizen of the United States, residing at Toledo, in the county of Lucas and State of Ohio, have invented certain new and useful 5 Improvements in Brake-Shoes, of which the following is a specification.

This invention relates to brake shoes and particularly those types of brake shoes or 10 wearing blocks which are used on the brakes of railway cars and locomotives, and especially to such types of those brake shoes as are provided with steel reinforcing backs and inserts cast into the wearing face of 15 the shoe at the time it is poured.

The principal objects of the present invention are the provision of a key lug of improved form for attaching the shoe to the brake head; the provision of an integral 20 lug which may not be detached from the body of the shoe or the reinforcing members without destruction of the continuity of the lug or the parts with which it has engagement, to the end that the shoe may not be 25 come disengaged from the head and thereby cause derailment of the car to which it is applied; the provision of an attaching lug which will be rigid and resist both longitudinal and transverse stresses received in 30 shipping and in service, and which has means for guiding the passage of the brake shoe key therethrough, and the provision of a filler block which will prevent the flow of the metal of the body of the shoe up into 35 the lug at the time of casting, all so arranged that a shoe embodying my invention may be manufactured more inexpensively than in other ways at present known to me, and may be applied to a brake head 40 with greater facility and accuracy and with less danger of canting or other misplacement which causes the shoe to wear unevenly, break prematurely and hence be uneconomical and inefficient in operation; the provision 45 of improved forms of "inserts" which may be either harder or softer than the metal of the cast body of the shoe, or alternately both, whereby both the frictional and the wearing qualities of the shoe may 50 be regulated with nicety and shoes of any degree of hardness produced with accuracy by varying the quality or number of inserts applied to the wearing face thereof.

The above together with such other objects as will hereinafter appear and further

benefits and advantages which will readily occur to those who are skilled in the art to which my invention pertains, I accomplish by means of the construction which I have illustrated in the accompanying drawings wherein—

Figure 1 is a longitudinal elevation, partly in section, of a brake shoe embodying my improvements;

Fig. 2 is a plan view illustrative of the 65 wearing face of the shoe shown in Fig. 1.

Fig. 3 is a perspective view of a number of the inserts appearing in Figs. 1 and 2.

Fig. 4 is a transverse section of the shoe 70 illustrated in Figs. 1 and 2.

Fig. 5 is a perspective view of the attaching lug shown in section in Fig. 1.

Fig. 6 is a perspective view of the filler block used for reinforcing the lug of Fig. 5, and of Figs. 7, 8, 9, 10 and 12, which figures illustrate modifications in the form of the lug shown in Fig. 5.

Fig. 11 is a plan view of a stamping from which the lug of Fig. 12 is formed.

Referring to Figs. 1 to 4 it will be observed that in carrying out my invention I provide the usual cast body portion or wearing face 14 and for the purpose of reinforcing the shoe, I provide the body portion thereof at the back with one or more 85 strengthening members such for example as the flat straps 15, 16 and 17, which I preferably provide with rounded edges 18 and 19 in order to insure a firmer engagement with the body of the shoe, which straps 90 are here shown as provided with end portions of greater breadth than the intermediate portions thereof in order that no part of the body of the shoe may become disengaged from such straps in the event of the 95 breakage of such body. The widening of the ends of the straps may be accomplished by slitting as indicated at 20 and 21 and spreading the opposite portions 22 and 23, and 24 and 25, or in other ways which will 100 readily occur to those who are skilled in the art.

In order to produce a shoe of maximum longevity and at the same time one which is of the highest frictional powers, I have 105 provided the arrangement of inserts illustrated in Figs. 1 to 4 in preferred form, wherein I make use of steel, wrought iron, or other hard metal blocks 26 in order to retard the wearing away of the frictional 110

face of the shoe, and for wheel dressing and other well known purposes, and alternately therebetween blocks of gray iron, cast metal, or other comparatively soft substances of a highly frictional nature.

5 In practice I find it most convenient in the manufacture of my improved shoes to place in one half of the mold in which the shoes are to be cast a chill block 29, upon 10 which I place the blocks 26 and 27 mounted alternately upon a doubled wire 30, (see Fig. 3), which may then be twisted by the pin 31 until the blocks assume the position indicated most clearly, in Fig. 1.

15 It will be observed further from Fig. 3 that the several elements of one of the series of blocks 26 and 27, preferably the cast blocks 27, are provided with projections such as illustrated at 32, 33, 34 and 35, which 20 I have found useful to make of substantially the same width as the block, in order to space the several members of the two series a sufficient distance from each other for the purpose to be now described.

25 This procedure and arrangement of parts serves a two fold purpose, viz., as the cast metal of the body of the shoe 14 flows between the several blocks 26 and 27, as indicated at 28, it comes into contact with the 30 chill block 29 and is hardened to a degree intermediate between that of the frictional blocks 26 and the dressing blocks 27, and at the same time all of the blocks 26 and 27 are tied together in the cast metal 28 by the 35 wire 30.

It will thus be seen that not only will it be impossible for any of the inserts 26 and 27 to become disengaged from the body of the shoe and drop out of it, but also that 40 there is no sharp line of demarcation between the hard and soft portions of the wearing face, as the intermediate portions 28 tend to blend one into the other gradually, and scoring of the tread of the wheel 45 to which the shoe is applied is thereby avoided.

By reference to Figs. 2 and 4, it will be noted that my improved forms of inserts and means for fixing them in the cast metal 50 of the shoe is equally adaptable to the flange type of shoe as to the plain or ball types, 36 being the harder inserts and 37 the softer inserts, which are brought into position by a wire as illustrated in Fig. 3, upon a chill 55 block 39, for the purposes above described.

In Fig. 5, I have shown a perspective view of the attaching lug illustrated at 40 in Fig. 1, and in Fig. 6 a like view of the filler block 41, which I use for the purpose of reinforcing and stiffening the lug 40 and to 60 avoid the necessity of using cores for preventing the cast metal of the body of the shoe from entering and filling the lug at the time of pouring the shoe.

65 It will be apparent that by virtue of the

provision of the said filler block 41, and of the depressed portion 42 of the top of the said lug 40 not only is the brake shoe key more readily passed through the key-way in such lug, but it also finds a much firmer seat 70 therein.

In Fig. 7 I have illustrated a modified form of lug which may be used in shoes where rods are found desirable in place of straps, or where no reinforcement at all 75 is used but reliance is placed upon the passage of the cast metal of the body of the shoe through the apertures 43, 44 and 45 instead of the straps 16 and 17 through apertures such as 46 and 47. This type of lug 80 may be cut away or dovetailed as indicated at 48, 49 and 50, in order to give further engagement with the cast metal of the body of the shoe, although it is obvious that the reinforcing filler blocks 41 may also be utilized if desirable.

In Figs. 8, 9 and 10 I have illustrated further modifications in the form of the depressed portions 42, and in Fig. 11 a blank from which the lug of Fig. 12 may be 90 formed without cutting away the blank as indicated at 51 and 52 in Fig. 5 or as indicated in the structures illustrated in Figs. 7 to 10.

It will be apparent to those who are 95 skilled in the art that other modifications of my inventions may be designed for the purposes above set forth.

Having thus described my invention and illustrated its uses, what I claim as new 100 and desire to secure by Letters Patent is the following:

1. In combination with a hanger and its connecting key, a brake shoe having a stiffening back, a body of cast metal, and a separate attaching lug fixed in said body and of box-like form, and a reinforce for said lug. 105

2. In combination with a brake shoe comprising a wearing face and a reinforcing back embodied therein, a separate attaching lug of box like form engaging said wearing face and back. 110

3. In a brake shoe, a unitary wrought metal attaching lug, comprising top, side and end portions, said side and end portions 115 being separate but approximately contiguous, and said top portion being provided with a depressed bearing surface for the attaching key, substantially as described.

4. In a brake shoe, an attaching lug having top, sides and ends, a key-way through said sides for receiving the brake shoe key and a depression in said top for guiding the key through the key-way. 120

5. In a brake shoe, in combination, a body 125 portion, an attaching lug fixed in said body and a solid reinforcing filler block in said attaching lug.

6. In a brake shoe, in combination with a body portion, an attaching lug fixed in said 130

body and having a key-way and a reinforcing filler in said attaching lug between said key-way and body portion.

7. In a brake shoe, in combination, a body portion, a wrought metal attaching lug of box like form and a solid filler block for reinforcing said lug.

8. In a brake shoe, a body portion, a separate attaching lug fixed in said body portion, a flat strap passed through said lug and a filler block for reinforcing and stiffening said lug.

9. In a brake shoe, a body portion, a separate attaching lug fixed in said body portion, a flat strap passed through said lug and a filler block for reinforcing and stiffening said lug, the top portion of said lug being depressed.

10. In combination with a hanger and its connecting key, a brake shoe having a lug

of sheet metal fixed to the back of said shoe for supporting said shoe through said key and having its top depressed thereby forming an inwardly extending bearing thereon adapted to bear upon said key.

11. In combination with a hanger and its connecting key, a brake shoe having a lug of sheet metal fixed to the back of said shoe for supporting said shoe through said key and having its top depressed and flattened thereby forming an inwardly extending bearing thereon adapted to bear upon said key.

In testimony whereof I have hereunto signed my name in the presence of the subscribed witnesses.

FRANK T. DICKINSON.
